BLASTING AND DYNAMITING

Edmund Karollus, Vienna, Austria

Application November 2, 1932, Serial No. 640,818

5 Claims. (Cl. 102—11)

The present invention relates to blasting and dynamiting operations.

For many years, in blasting and dynamiting operations it has been customary, after preparing a bore of suitable depth, position and dimension in the ground or in the material to be blasted, to place a plurality of elongated cylindrical dynamiting cartridges therein in such a manner that their ends will contact and they will form a substantially solid column of explosive material. This column of explosive material will extend from the bottom of the bore over the entire area to be blasted. An explosive blasting cap or cartridge is usually inserted in the uppermost stick of explosive or dynamite material. From this cartridge wires or a fuse cord are extended to the top of the bore, so that it is possible to ignite and explode the dynamite column by either lighting the fuse or by electrical means upon the surface. After the explosive cartridge has been placed in position, earth or other solid material is at first loosely placed in position for a substantial distance above the uppermost cartridge and then the remaining portion of the bore to substantially the surface is compactly filled with earth or other material.

In this blasting or dynamiting operation just described, it has always been customary to attempt to decrease the air spaces in the bore as much as possible. The dynamite or explosive cylinders desirably fill the hole or bore as closely as possible. It has also been thought necessary to have the dynamite or explosive sticks or cylinders closely contact each other as otherwise it appeared that the explosion would not take place in the desired manner and that there was a possibility that some of the sticks would not be ignited. The method just described, however, required the utilization of a relatively large quantity of the blasting material without appearing to fully utilize the blasting efficiency thereof. Furthermore, instead of merely heaving the surrounding soil or mineral and breaking it up into relatively large particles or lumps, there was a pronounced shattering effect with the production of an excessive amount of fines.

An object of the present invention is to carry out and/or perform the blasting and dynamiting operation in such a manner as to permit of considerable economy in the utilization of explosive or dynamite material and at the same time secure a rupture or breaking up of the soil and other material into relatively large lumps of desired size, without the production of an excessive amount of fines and without undue shattering.

Other objects will appear during the course of the following specification.

It has been found that if the height of the explosive column, instead of being substantially compactly filled with an explosive material, be in part made up of inert solid materials, there is no substantial loss in the blasting efficiency and, at the same time, the operation results in the production of a broken up material of particularly desirable qualities. These inert materials or spacing materials which may be utilized to make up the height of the explosive column should preferably be of non-metallic materials, and should preferably provide a substantial air space in respect to the wall of the bore. These spacers, in addition, should be suitably constructed so as to assure that the explosive flame will be transmitted from one explosive cartridge to the next.

In one embodiment of the present invention it has been found desirable to provide wooden cylinders having a central bore or opening therein, which wooden cylinders are preferably of substantially less diameter than the bore diameter. It is to be understood, however, that the invention is not to be restricted to wooden cylinders, as blocks of any other solid inert material may be utilized, said blocks, however, being of such a material as not to cause the production of sparks and danger of pre-ignition of the explosive material and also being of such construction as to assure transmission of the ignition flame from one explosive cartridge to the next.

In commercial practice it has been found most satisfactory to make the spacer blocks or cartridges of substantially the same height and diameter as the explosive cartridges. In forming the explosive column in the previously prepared hole or bore, most satisfactory explosive efficiency has been obtained when the proportion of the height of the column occupied by the spacer blocks constitutes between 0.2 to 0.45 of the total of the height of the explosive column, with a maximum efficiency being had when the spacer blocks average about 0.33 of the height of the total column. Preferably in all cases the spacer blocks should constitute substantially less than 0.5 and substantially more than 0.15 of the total explosive column.

When, as in the preferable commercial embodiment, the spacer blocks are substantially the same length and shape as the explosive cartridges, it is usually desirable to form the explosive column in such a way that the top and bottom elements of the column consist of explosive cartridges while in the length of the column not more than

a single spacer block is utilized to separate any two explosive cartridges. It has usually been found desirable to increase the amount of explosive material in the column adjacent the bottom or the lower end of the bore or hole so that if two explosive cartridges are to be placed in contact they are preferably located adjacent such bottom.

Upon the accompanying drawing are shown diagrammatically several illustrative methods of carrying out the exploding operation of the present invention.

In the drawing, Figs. 1, 2 and 3 show different manners of preparing and forming the blasting or explosive column.

In Figs. 1, 2 and 3 the hole or bore 10 is suitably provided and positioned and is made of slightly larger diameter than the explosive cartridges to be placed therein. The explosive cartridges 11 and the spacer blocks 12 are preferably both of generally cylindrical form and they are desirably placed so as to closely contact with each other and form a substantially solid column.

One of the cartridges 11, for example the uppermost explosive cartridge, may be provided with a blasting or explosive element 13, which is connected to the wire or fuse 14, extending to the surface. Above the uppermost cartridge the hole or bore is filled with dirt or other material 15.

It will be noted in Figs. 1, 2 and 3 that the column is always made in such a way that there will be an explosive cartridge 11 at the top and bottom thereof and so that if it is necessary to place two explosive cartridges in contact this is done at the bottom of the column. It will also be noted that in any case the explosive sticks or cylinders 11 are not separated by more than one spacer 12.

The spacer blocks, as previously stated, are desirably of cylindrical shape and are of such diameter as to permit a spacing 16 through which the explosive flame may travel from one explosive cylinder 11 to the next. Since, however, the space 16 may in some instances fill with dirt or other loose material, another opening 17 is provided centrally through each spacer 12, which will remain open and assure transmission of the ignition flame between the explosive sticks or cylinders 11 past the spacer blocks 12.

In one commercial embodiment it has been found satisfactory to make the spacer blocks about 32 millimeters in diameter with a central opening of about 7 millimeters in diameter and of a height of about 30 centimeters in length. However, the dimension of the spacer elements is usually varied in accordance with the size of the dynamite and explosive sticks and the size of the hole or bore which is to be prepared.

By constructing an explosive column in this manner there is both a very marked saving in powder or explosive material, averaging from one-half to one-third, and, moreover, a more satisfactory breaking up of the material is obtained with a substantial reduction in the amount of the fines and with the production of coarser pieces. Moreover, there is a greater reduction in the amount of poisonous gases produced with an additional saving in the amount of expenditure and time necessary to exhaust and remove such undesired gases.

The present invention, in utilizing wooden spacer blocks substantially filling the width and diameter of the bore, has marked advantages over spacing the successive sticks or cylinders of explosive material with an air column or with con-

tainers of a fluid such as water. When the successive sticks or cylinders of dynamite or explosive material are spaced by means of an open frame-work or trellis, as of wood, there is a substantial air space much greater than that needed to convey the ignition flame from one explosive cylinder to the next. As a result the gases resulting from the explosion will expand into this relatively wide open space and greatly decrease the efficiency of the blasting operation. On the other hand, the provision of spacer cylinders containing water and other fluids, which will turn into a vapor, are not altogether satisfactory, since these spacer cylinders are both expensive and, moreover, considerable energy of the explosion is taken up when vaporizing the water, without the steam resulting contributing substantially to the blasting efficiency. The utilization of water containing spacers also hinders or obstructs the transmission of the flame from one cartridge to the next.

As many changes could be made in the above construction, and many apparently widely different embodiments of this invention could be devised without departing from the scope thereof, it is intended that all matter contained in the above description or shown in the accompanying drawing shall be interpreted as illustrative and not in a limiting sense.

What is claimed is:

1. An explosive column for use in dynamiting or blasting operations, comprising a plurality of charges of explosive material, substantially solid spacer elements of inert material disposed between the explosive charges, said spacer elements having a cross sectional area slightly less than the cross sectional area of the explosive charges, whereby an air space exists between charges sufficient to convey the ignition flame from one charge to the next but insufficient to permit any substantial expansion of the gases discharged upon ignition.

2. An explosive column for use in dynamiting or blasting operations, comprising a plurality of charges of explosive material, substantially solid spacer elements of inert material disposed between the explosive charges, said spacer elements having a cross sectional area slightly less than the cross sectional area of the explosive charges, and provided with a passage for permitting the ignition flame to pass from one charge to the next, whereby an air space exists between charges sufficient to convey the ignition flame from one charge to the next but insufficient to permit any substantial expansion of the gases discharged upon ignition.

3. An explosive column for use in dynamiting or blasting operations, comprising charges of explosive material, said charges having a cross sectional area substantially equal to the cross sectional area of the hole in which they are intended for use, substantially solid spacer elements of inert material disposed between the explosive charges, said spacer elements having a cross sectional area less than the cross sectional area of the explosive charges, whereby an air space exists between charges sufficient to convey the ignition flame from one charge to the next but insufficient to permit any substantial expansion of the gases discharged upon ignition.

4. An explosive column for use in dynamiting or blasting operations, comprising a plurality of charges of explosive material, substantially solid spacer elements of inert material disposed between the explosive charges, said spacer elements
